UNITED STATES PATENT OFFICE

JOHN K. OLSEN, OF CHICAGO, ILLINOIS, ASSIGNOR TO STEWART-WARNER CORPORATION, OF CHICAGO, ILLINOIS, A CORPORATION OF VIRGINIA

DESIGN FOR A REFRIGERATOR CASING

Application filed August 10, 1932. Serial No. 44,569. Term of patent 7 years.

To all whom it may concern:

Be it known that I, JOHN K. OLSEN, a citizen of the United States, having residence at Chicago, in the county of Cook and State of Illinois, have invented a new, original, and ornamental Design for a Refrigerator Casing, of which the following is a specification, reference being had to the accompanying drawing, forming a part thereof,

The drawing is a perspective view of a refrigerator casing embodying my new design.

I claim:

The ornamental design for a refrigerator casing, substantially as shown.

JOHN K. OLSEN.
